CLAIM

The ornamental design for a remotely transmitted temperature receiver and cradle, as shown and described.

DESCRIPTION

FIG. 1 is a top plan view of a remotely transmitted temperature receiver and cradle showing my new design;

FIG. 2 is a right side elevational view thereof, the left side being a mirror image thereof;

FIG. 3 is a rear elevational view thereof;

FIG. 4 is a front elevational view thereof;

FIG. 5 is a bottom plan view thereof.

FIG. 1

FIG. 2

FIG. 5

FIG. 3

FIG. 4
